JOHN H. PILLINGS, OF HAMILTON, OHIO, ASSIGNOR TO HOOVEN AUTOMATIC TYPE-WRITER CORPORATION, OF HAMILTON, OHIO, A CORPORATION OF NEW YORK

MECHANISM FOR AUTOMATICALLY OPERATING LEVERS AND THE LIKE.

1,357,514.

Specification of Letters Patent.

Patented Nov. 2, 1920.

Application filed July 9, 1919. Serial No. 309,697.

To all whom it may concern:

Be it known that I, JOHN H. PILLINGS, a citizen of the United States, residing at Hamilton, in the county of Butler and State 5 of Ohio, have invented a certain new and useful Improvement in Mechanism for Automatically Operating Levers and the like, of which the following is a full, clear, and exact description.

10 This invention relates to mechanism by which a plurality of levers or other moving parts may be automatically operated in proper sequence as determined by perforations in a controller strip.

15 The invention is in the nature of an improvement upon the mechanism for the same purpose which forms the subject matter of the McCall Patent No. 1,024,092, and my own prior Patent No. 1,174,090. Each 20 of these patents shows the mechanism in a form especially adapted for use in combination with a typewriting machine in order that said machine may automatically write "form" letters.

25 The present invention is also shown in a form especially adapted for this particular purpose; although it obviously is adapted for use in automatically operating the keys and other parts of other machines, as for example, musical instruments.

30 Generally, speaking, the objects of this invention are to provide, for the stated purpose, mechanism which, as compared with the mechanisms of said prior patents, will 35 cost less, be more efficient, and less liable to break and get out of order, and which may be more easily assembled and disassembled when necessary.

With these and other ends in view, which 40 will subsequently appear, the invention consists in the construction and combination of parts shown in the drawing, hereinafter described and definitely pointed out in the appended claims.

45 In the drawing, Figure 1 is a side elevation, partly sectioned showing the invention associated with a typewriter machine; Fig. 2 is a front elevation of such mechanism and a part of the typewriter mechanism, and 50 Fig. 3 is a plan view showing some of the typewriter key levers and the parts immediately associated therewith which are parts of the present invention.

The present invention includes a plurality of vertical hangers 10 arranged side by side, cross-wise of the machine, one for each of the typewriter key levers 40 or other instrumentalities of the typewriter which it is desired to operate from time to time. 55

Associated with each of those hangers is 60 a pawl 20 which is pivotally connected with the hanger and extends forward therefrom, and has at its front end an integral pin or point 21 which normally rests on the unperforated surface of a controller strip S 65 which runs over and is carried along by a rotating cylinder 30. In this cylinder are circumferential rows of pockets 31, which are separated by teeth 32. Whenever a perforation in the controller strip passes beneath the pointed end 21 of a pawl 20, this end will drop through the perforation into one of the pockets 31 and in front of one of the teeth 32. As the result of this since the cylinder is constantly rotating, the pawl will 70 be displaced rearwardly, and it will cause corresponding rearward movement of that hanger with which it is associated. 75

Each hanger has upon its rear side a shoulder 12 which when the hanger is displaced rearwardly will come beneath the front edge of a depresser bar 60 which is constantly moving up and down through a limited path. When this depresser bar engages the shoulder 12 of a displaced hanger 80 the hanger is moved down. A part carried by the hanger, which will presently be explained in detail, engages with the key lever 40 or some other part of the typewriting 85 machine, and imparts to it the movement required to enable it to perform the function for which it is provided.

The depresser bar is common to the various hangers; and the cylinder 30 has a common relation to all of the associated 90 pawls 20, and it operates that one of the pawls whose point falls through a perforation in the controller strip. The various 95 hangers and their associated pawls 20 are substantially alike, and they are supported 100 and guided by the following means: There is a transversely extended bar 17 in the upper ends of which are narrow vertical slots 17^a, and one of the hangers is slidably vertically in each of these slots. 105

Each hanger passes upward alongside of

the key 40 with which it is associated. Secured to the upper end of each hanger above the key lever is a little block 13. A screw 14 screws down through this block until its lower end is at the proper distance above the associated key lever 40. On the rear side of each block is a little tongue 15 which slidably fits in the same slot 16^a in a bar 16 of the typewriting machine through which the associated key lever 40 passes. The lower end of the hanger is therefore guided in a slot in the bar 17 while the upper end of the hanger is guided by the engagement of the tongue 15 in the slot in a part 16 of the typewriter machine. The forwardly projecting part of the block 13 lies beneath a horizontal transverse bar 18 in the lower edge of which is a strip of fiber, rubber or other sound deadening material 18^a against which the block 13 will strike as it is moved upward.

The lower end of each of the hangers is provided with a downwardly extended tail piece 19 which, when the hanger is in its normal position, rests against a finished surface 17^b on the rear face of the comb block 17. A spring 52 engages with this tail piece 19, and acts to force it against the bar 17 when that is possible. A spring 54 is also associated with each hanger. This is a small coil spring which is seated in a recess 55 in the block 17,—its projecting upper end surrounding a little pin 11 fixed to the lower end of the hanger.

From the foregoing it will appear that whenever the point 21 of any pawl 20 drops through a perforation in the controller strip S, it will be immediately engaged by the cylinder 30 and pushed rearward. As it moves rearward the hanger will also move rearward so as to carry its shoulder 12 beneath the constantly reciprocating depresser bar 60; whereupon the hanger will be depressed and the lever 20 will be rocked; the screw carried by the hanger will engage the associated lever 40, whereby said lever will be operated. Then as the depresser bar moves upward, the spring 53 will move the hanger upward and the spring 52 will move the hanger forward into its normal position in which its shoulder 12 is no longer in the path of the depresser bar.

A guard plate 70 is pivoted at its lower end on a transverse pivot 71 to the bar 17 and it extends upwardly therefrom fairly close to the strip S which is passing the cylinder 30. This guard plate carries a transversely extended rod 72 which lies beneath all of the pawls 20, and in such position that when a pawl is displaced rearward and the associated hanger is moved down, the pawl will be brought into contact with the bar 72; and will then fulcrum and rock thereon with the result of lifting the front end 21 of the pawl out of engagement with the cylinder and above the surface of the

controller strip S. When a hanger has been restored to its normal position, this pawl will automatically rock back to the position in which its front pointed end rests upon the surface of the controller strip. 70

A transverse bar 77 extends over all of the pawls 20, the function of said bar being to limit the upward movement of the pawls 20 as the associated hangers are moved downward. 75

The upper end of the guard plate 70 is formed with a comb slot 72^a for each of the pawls 20; and each pawl passes through one of these comb slots and is thereby kept in proper operative position. Whenever it is desired to put in a new controller strip S this guard plate is swung upward and rearwardly upon its pivot; the bottoms of all of the comb slots engage the lower surface of the pawls 20 and thereby swing all 85 of said pawls upward so that their front ends will be well above the surface of the cylinder. To enable this to be done a little rock shaft 80 is pivoted to the frame work of the mechanism. An operating lever 81 is 90 fixed to it and so also is a cam 82 which is shown in dotted lines in Fig. 1, which cam engages the lower surface of the guard plate. Swinging the lever 81 rearwardly the cam shaft is rocked and the cam 82 will 95 engage the guard plate and rock it upon its pivot with the result above described.

The specific cylinder 30, as shown, is made up of alternate toothed wheels 33 and spacing disks 34 all of which are mounted 100 and nonrotatably secured upon a central arbor 35 in contact with one another. It will be noted that the spacing disks have no teeth, and also that their diameters are such that they project out beyond the bottoms 105 of the pockets 31 to or substantially to the outer ends of the teeth 32. They therefore serve as side walls of said pockets and separate the circumferential rows of pockets from one another. A worm wheel 110 36 is secured to this arbor, and this is engaged by a constantly driven worm 37 whereby the cylinder is constantly rotated.

In the particular construction shown each pawl 20 has a cylindrical rear end 23, and 115 this fits in a cylindrical hole 25 in the associated hanger, there being a slot 26 extending from this hole through the front end of the hanger for the passage of the reduced neck 27 of the pawl. These pawls 20 120 are of the same thickness as the hangers, and the rear end of each pawl is held in the circular hole in the hanger by the side walls of the slots in which the hangers slide. This simplifies and cheapens the construction, 125 and renders the operative connection of each pawl with its hanger easy and inexpensive as compared with any other form of pivotal connection.

The depresser bar 60 may be connected 130

with two arms 61 both of which are connected with a rock shaft 62. This rock shaft may have a rearwardly extended arm 63 which is engaged by an eccentric strap 64, the lower end of which embraces an eccentric 65, on the same shaft 38 which carries the worm 37.

Having described my invention, I claim:—

10 1. In mechanism of the character specified, the combination of a rotatably pock-
eted cylinder, a perforated controller strip
which runs over said cylinder, a vertically
movable hanger, a pawl pivoted to said
hanger and extended therefrom over said
cylinder and having a point adapted to rest
upon the controller strip and to drop
through the holes therein into a pocket in
said cylinder whereby the pawl and hanger
will be displaced rearwardly, and means for
moving the displaced hanger downward.

15 2. In mechanism of the character specified, the combination of a rotatably pock-
eted cylinder, a perforated controller strip
which runs over said cylinder, a vertically
movable hanger, a pawl pivoted to said
hanger and extended therefrom over said
cylinder and having a point adapted to rest
upon the controller strip and to drop
through the holes therein into a pocket in
said cylinder whereby the pawl and hanger
will be displaced rearwardly, means for
moving the displaced hanger downward, a spring
35 for elevating the hanger, a spring for
moving the hanger forward, and a stop
to limit that forward movement.

30 3. In mechanism of the character specified, the combination of a rotatably pock-
eted cylinder, a perforated controller strip
40 which runs over said cylinder, a vertically
movable hanger, a pawl pivoted to said
hanger and extended therefrom over said
cylinder and having a point adapted to rest
upon the controller strip and to drop
45 through the holes therein into a pocket in
said cylinder whereby the pawl and hanger
will be displaced rearwardly, and means for
engaging the displaced hanger to move it
downward, a bar which lies beneath the
50 pawl in such position that when the hanger
is depressed the pawl will engage said bar
and have its front end lifted out of engage-
ment with said cylinder.

4. In mechanism of the character specified, the combination of a rotatably pock-
eted cylinder, a perforated controller strip
which runs over said cylinder, a vertically
movable hanger, a pawl pivoted to said
hanger and extended therefrom over said
60 cylinder and having a point adapted to rest
upon the controller strip and to drop
through the holes therein into a groove in
said cylinder whereby the pawl and hanger
will be displaced rearwardly, and means for
65 engaging the displaced hanger to move it

downward, and means for restoring the dis-
placed hanger and pawl to their normal po-
sition.

5. In mechanism of the character speci-
fied, the combination of a rotatably pock-
eted cylinder, a perforated controller strip
which runs over said cylinder, a vertically
movable hanger, a pawl pivoted to said
hanger and extended therefrom over said
cylinder and having a point adapted to 70
rest upon the controller strip and to drop
through the holes therein into a pocket in
said cylinder whereby the pawl and hanger
will be displaced rearwardly, and means for
engaging the displaced hanger to move it 75
downward, a bar which lies beneath the
pawl in such position that when the hanger
is depressed the lever will engage said bar
and have its front end lifted out of engage-
ment with said cylinder, means for raising 80
said bar and thereby lifting the front end
of the pawl out of engagement with the con-
troller strip.

6. In mechanism of the character speci-
fied, the combination of a rotatably pocketed 90
cylinder, a perforated controller strip which
runs over said cylinder, a vertically movable
hanger, a pawl pivoted to said hanger and
extended therefrom over said cylinder and
having a point adapted to rest upon the con-
troller strip and to drop through the holes 95
therein into a pocket in said cylinder where-
by the pawl and hanger will be displaced
rearwardly, and means for engaging the dis-
placed hanger to move it downward, means 100
for restoring the displaced hanger and pawl
to their normal positions, and a guard bar
which overlies the pawl and limits its up-
ward movement.

7. In mechanism of the character speci-
fied, the combination of a rotatably pocketed
cylinder, a perforated controller strip which
runs over said cylinder, a vertically movable
hanger, a pawl pivoted to said hanger and
extended therefrom over said cylinder and
having a point adapted to rest upon the con-
troller strip and to drop through the 110
holes therein into a pocket in said cylinder
whereby the pawl and hanger will be dis-
placed rearwardly, and means for engaging 115
the displaced hanger to move it downward,
a block fixed to the side of said hanger, and
a movable member located below said block
in position to be engaged by a part of the
same when the hanger is depressed. 120

8. In mechanism of the character speci-
fied, the combination of a rotatably pocketed
cylinder, a perforated controller strip which
runs over said cylinder, a vertically movable
hanger, a pawl pivoted to said hanger and
extended therefrom over said cylinder and
having a point adapted to rest upon the
controller strip and to drop through the
holes therein into a pocket in said cylinder
whereby the pawl and hanger will be dis- 125
130

placed rearwardly, and means for engaging the displaced hanger to move it downward, a block fixed to the side of said hanger, a set screw which screws down through said block 5 and projects below the same, and a movable member located below the lower end of said screw in position to be engaged thereby when the hanger is moved down.

9. In mechanism of the character specified, the combination of a rotatably pocketed cylinder, a perforated controller strip which runs over said cylinder, a vertically movable hanger, a pawl pivoted to said hanger and extended therefrom over said cylinder 15 and having a point adapted to rest upon the controller strip and to drop through the holes therein into a pocket in said cylinder whereby the lever and hanger will be displaced rearwardly, and means for engaging 20 the displaced hanger to move it downward, a guard plate pivoted at its lower end and extended partly over said cylinder said guard plate having vertical slots in its upper edge, and the pawl being loosely fitted 25 in one of said slots, and means for swinging said guard plate upward to lift the pawl out of engagement with the controller strip.

10. In mechanism of the character specified, the combination of a rotatably pocketed cylinder, a perforated controller strip which runs over said cylinder, a plurality of vertically movable hangers, a pawl pivoted to each hanger having a point adapted to ride 30 upon the controller strip and to drop through holes therein into engagement with said cylinder, a lower comb bar having guide 35 grooves for said hangers, an upper comb

bar, a block fixed to the side of each hanger having a tongue which is slidably fitted in a groove in said upper comb bar, a transverse bar extending in front of the upper ends of said hangers and overlying the blocks attached thereto, means for depressing each displaced hanger, and levers located respectively below the block secured to the 40 hangers in position to be engaged by devices carried by said blocks.

11. In mechanism of the character specified, the combination of a rotatably pocketed cylinder, a perforated controller strip which runs over said cylinder, a vertically movable hanger, a pawl having a point adapted to rest upon the controller strip and to drop through holes therein into a groove in said cylinder whereby the pawl will be displaced 50 rearwardly,—said hanger having a transversely extended cylindrical notch in its edge and the pawl having a cylindrical rear end which fits said notch, a comb bar having a narrow groove in which is slidably 55 fitted that part of said hanger with which the pawl engages as stated, and means for moving the displaced hanger downward.

12. In mechanism of the character specified, a cylinder for supporting and driving 60 a perforated controller strip comprising a central arbor and alternately placed toothed and plain disks which are nonrotatably secured upon said arbor in contact with one another.

In testimony whereof, I hereunto affix my signature.

JOHN H. PILLINGS.
